UNITED STATES PATENT OFFICE.

JAMES HARGREAVES, OF FARNWORTH, COUNTY OF LANCASTER, ENGLAND.

INTERNAL COMBUSTION THERMO-MOTOR.

SPECIFICATION forming part of Letters Patent No. 431,581, dated July 8, 1890.

Application filed February 24, 1890. Serial No. 341,385. (No model.) Patented in England August 28, 1888, No. 12,361; in France July 3, 1889, No. 199,343; in Italy July 8, 1889, No. 25,804; in Germany July 11, 1889, No. 50,592; in Belgium July 15, 1889, No. 86,863, and in Spain September 18, 1889, No. 9,798.

To all whom it may concern:

Be it known that I, JAMES HARGREAVES, chemical engineer, of Farnworth, in the county of Lancaster, England, have invented 5 a new and useful Improvement in Internal Combustion Thermo-Motors, (for which I have obtained a patent in Great Britain, No. 12,361, dated August 28, 1888; in France, No. 199,343, dated July 3, 1889; in Belgium, No. 86,863, 10 dated July 15, 1889; in Germany, No. 50,592, dated July 11, 1889; in Italy, No. 25,804, dated July 8, 1889; in Spain, No. 9,798, dated September 18, 1889, and nowhere else;) and I do hereby declare the following to be a full, clear, 15 and exact description thereof.

My invention relates to an improvement in motors which are driven by power obtained from the combustion of liquid or gaseous fuel and air within a working chamber or 20 cylinder; and the object is to provide a motor of simple and durable construction and efficient action.

Figure 1 is a vertical section of a motor under my invention. Fig. 2 is a horizontal 25 section thereof at the line A A in Fig. 1, and Fig. 3 a vertical section thereof at the line B B in Fig. 2. Figs. 4 and 5 are sectional views showing modified constructions of the parts of Figs. 3 and 2, to which they are respectively adjacent on the sheet. Fig. 6 is an 30 enlarged view of part of the piston, showing means for lubricating; and Fig. 7 is an enlarged sectional view of the combustion-chamber lining. Fig. 8 is an end view of the 35 piston, showing the covering. Fig. 9 is a perspective view, enlarged, of the covering for the piston-face; and Fig. 10 is an enlarged view of the fuel-injector.

1 is the working-cylinder, fitted with a metallic liner 2. 40 3 is the combustion-chamber, cast in one piece with the working-cylinder. The sides or walls 3 of the combustion-chamber are lined with fire-brick blocks or segments 4 or 45 with cement, and such blocks are held in position by longitudinal metal T-shaped stays 5, secured to the walls of the combustion-chamber.

6 is a jacket surrounding the combustion-

chamber and working-cylinder. The space 50 between the jacket and the cylinder and combustion-chamber walls is partly filled with water, so that the lower part serves more particularly as a cooler for the iron work and for generating steam, while the upper part 55 serves as a saturator and superheater.

7 is a regenerator partially outside and partially within the side of the water-jacket 6.

8 is a way for charging the regenerator 7 with loose pieces of refractory material. 60

9 is a closing-plug.

10 is a passage leading from the regenerator 7 to the combustion-chamber 3.

11 is an injector provided with a lip 12 for forcing liquid fuel in the form of spray into 65 the passage 10, so as to direct the fuel in the line of the air-passage and secure intimate admixture of the said fuel and air.

13 is a working-piston faced with steel plates 14, held in position by claws 15. The space 70 between the plates and the piston is filled with asbestos or asbestos and tar or like non-conducting and heat-resisting material, so that excessive heat is not conveyed to the body of the piston.

16 is a lubricator secured to the junk-ring 17 of the piston and having a way 18, leading to the back of the packing-rings 19. In this way efficient lubrication of the moving 75 parts is secured.

20 is a ring secured between the working-cylinder and combustion-chamber for the purpose of scraping the surface of the piston and preventing tarry matter from reaching the inside of the working-cylinder. 80

21 is an air-pump cylinder and piston.

22 are connections between the working-piston and air-pump piston.

23 is the crank-shaft.

24 is the connecting-rod. 90

25 is a way leading from the air-pump to the jacket 6, and having at its end a perforated box or plate by which the air-current is broken up and caused to enter the water in jets. 95

26 is a way leading from the jacket 6 to the regenerator 7 and past the admission-valve 27.

28 is the exhaust-valve.

29 is a way leading from the exhaust-valve to the uptake 30, which passes through the air-supply way 25.

5 The admission and exhaust valves are operated by cams or tappets in any usual way.

31 is a governor attached to a throttle-valve in the air-supply way.

In thermo-motors under my invention air moistened by water is forced by the pump 21 through the way 25, where it becomes heated by products of combustion passing through the uptake 30. The heated air then passes through the water in the jacket 6, where it is saturated with water-vapor, thence through 15 the space above the water, where it is further heated, and finally through the regenerator into the passage 10, where it mixes with the liquid fuel supplied by the injector. The mixture then passes into the combustion-chamber, where it is burned. The products of combustion expelled from the combustion-chamber pass through the regenerator and away by the uptake 30.

In starting the motor initially a lamp burning petroleum or other burning-fluid or a gas-jet is placed opposite to the opening covered by the lid at A, Fig. 1, and the said cover is removed. Intense combustion is produced by a blast of air and makes the 25 generator and passage 10 red-hot. When they are thus heated, the lid is closed and the engine started, the air necessary for burning the sprayed fuel being taken from the water-jacket space for the first stroke or first few 30 strokes of the engine. When the engine is thus started, its internal combustion keeps the parts at sufficient heat to ignite the fuel.

In an application filed by me on February 24, 1890, Serial No. 341,386, I show and describe an internal combustion-motor having some of the parts of the motor herein described and illustrated, and I claim, *inter alia*, the following items: the combination, with the motor, of a regenerator having that portion adjacent to the combustion-chamber closely packed with refractory blocks and its distant portion filled with loosely-packed removable refractory blocks; also, the combination, with a cylinder having a refractory non-metallic lining and a regenerator arranged in juxtaposition thereto, of a refractory lined cover common to both and adapted to couple the cylinder and regenerator by a direct channel, and also doors or ports affording access 55 to said cylinder and channel.

I claim—

1. In a thermo-motor, the combination of a

combustion-chamber, a heating or regenerating chamber, a water-jacket, and an air-inlet leading to the water-jacket and from the 60 water-jacket to the regenerator, whereby the air is water-charged in the water-jacket and is heated in the regenerator prior to its entrance into the combustion-chamber, substantially as and for the purposes described. 65

2. In a thermo-motor, the combination, with the combustion-chamber and regenerator connected by a passage through which the air passes from the regenerator to the combustion-chamber, of a fuel-injector discharging 70 into said passage, substantially as and for the purposes described.

3. In a thermo-motor, the combination of a combustion-chamber, a heating or regenerating-chamber, a water-jacket, an air-inlet leading to the water-jacket and from the water-jacket to the regenerator, whereby the air is water-charged in the water-jacket and is heated in the regenerator prior to its entrance into the combustion-chamber, and an 75 air force-pump by which the air is forced through the water-jacket and regenerator, substantially as and for the purposes described.

4. In a thermo-motor, the combination of a 80 combustion-chamber, a heating or regenerating chamber, a water-jacket, an air-inlet leading to the water-jacket and from the water-jacket to the regenerator, whereby the air is water-charged in the water-jacket and is heated in the regenerator prior to its entrance into the combustion-chamber, and a heated passage through which the air passes 85 prior to its entrance into the water-jacket, substantially as and for the purposes described. 95

5. In a thermo-motor, the combination of a combustion-chamber, a heating or regenerating chamber, a water-jacket, an air-inlet leading to the water-jacket and from the water-jacket to the regenerator, whereby the air is water-charged in the water-jacket and is heated in the regenerator prior to its entrance into the combustion-chamber, and a perforated plate or box through which the 100 air enters the water-jacket, substantially as and for the purposes described. 105

In testimony whereof I have hereunto set my hand this 25th day of November, 1889.

JAMES HARGREAVES.
